ABSTRACT OF THE DISCLOSURE

In a resonance synthesizer for speech research, an input is fed to the speech synthesizer means from an analog input device wherein the selected parameters, those essential to all speech, are fed directly to the synthesizer means after filtering out generation transients and those other parameters which are generated are fed to a parameter switch which selects those parameters which are necessary for the speech output desired so that less than all the parameters generated are passed to the synthesizer means. The synthesizer means has two excitation circuits and three spectrum-shaping circuits, commonly referred to as resonance circuits.

BACKGROUND OF THE INVENTION

An acoustic phonetician needs both analytic and scientific tools: the former to study the behavior of natural speech, the latter to test perceptually the hypothesis he has developed. Reasonably satisfactory and moderately-priced analytic tools, such as the Kay Sona-Graph, have been commercially available for sometime. Synthesis, however, has been more of a problem. The known commercially available synthesizers are quite expensive. Investigators who are engineers or who have good engineering support have built their own experimental synthesizers, but others have had to do without.

Several synthesizers have been built in the past in an attempt to overcome the difficulties encountered in speech synthesis. An example of one of these synthesizers of the prior art is the terminal analog type. This prior art device is intrinsically capable of producing high-quality speech; however, it does have certain limitations. Synthesizers of this type do not have separate nasal circuits and those which do, are not acceptable for faithful synthesis, therefore, acceptable nasal sound, in these prior art devices, must be constructed by using the circuits for the oral resonances. The nasal consonants produced in this way seem quite acceptable, but there is no way for the synthesizer to produce nasalized vowels. Finally, in prior art synthesizers of this type there is a forced choice between turbulent and voiced energy, which makes it difficult to synthesize sounds in which both forms of excitation occur, such as the voiced fricatives.

These limitations of prior art synthesizers are overcome by the device of the present invention wherein a mixed excitation is possible, parameter selection is possible, and wherein a separate nasal circuit is provided so as to be able to produce nasalized vowels as well as nasal consonants. In addition, the parameter switch included in the present device, and described in more detail later on, enables only ten parameters to be passed to the synthesizer means instead of the usual fourteen, as is done in the prior art. Fourteen parameters could, however, be passed to the synthesizer means at a given time if that were also desired; however, in the present invention only ten channels are necessary for the parameter generation device, which, in the case of a digital computer being used as a parameter generation device, results in a substantial monetary saving due to the using of a lesser

2

number of channels than has been done in the prior art. The utilization of the parameter switch of the present invention results in a versatility of connection to drive means and driven means not present in prior art devices.

Another example of the prior art is a speech sound generating device described by Vermeulen et al., in Pat. No. 2,458,227, issued on Jan. 4, 1949. The Vermeulen device performs synthesis as well as analysis. Four resonances are utilized, each having fixed bandwidth and carrying a given frequency range, with a given resonance shape output from the resonance circuit. The resonant frequency control is a reactance tube control, utilizing two circuits to cover the first formant range of 200 to 800 cycles per second. There is no disclosed capability of mixed excitation, which is necessary for certain speech sounds. The configuration shown in Vermeulen is of the fixed variety. There is an amplitude control of the resonance circuits of Vermeulen, however, there is no anti-logarithmic control of this amplitude function which is necessary for a wide dynamic range. Furthermore, Vermeulen does not filter the generator parameters so as to remove the transients due to generation, such as "pops" and "clicks," from the synthesized output. The Vermeulen device, as is common in the prior art devices, passes all the generated parameters to the synthesizer means.

The device of the present invention overcomes the inherent limitations in the Vermeulen device by several novel innovations. Seven resonance circuits instead of the four of Vermeulen are utilized so as to provide better fidelity, especially on fricatives. These resonance circuits are parallel resonance circuits having adjustable bandwidths, the proper bandwidth being important to fidelity. A choice of resonance shapes may be gotten from the device of the present invention; i.e., the conjugate pole pair or the conjugate pole pair with a zero at zero frequency. The present invention utilizes a chopper-type control of the resonant frequency so as to be able to cover the first formant range with only one formant resonance circuit. In the circuit of the present invention, a parameter switch is utilized to minimize the number of inputs, such minimization being in accordance with the parameters necessary for the synthesis of a given speech sound. The circuit of the present invention has flexibility; for example, the inputs circuits can be readily adapted to different ranges of input parameter voltages. The resonance circuits of the present invention have an anti-logarithmic control for the amplitude parameter, which will be explained in more detail later on. Lastly, the parameter switch, as well as a separate parameter filter for those parameters not passed through the switch, filter out transients in the parameter signals, such as those due to generation and switching, so as to eliminate the "pops" and "clicks" from the synthesized output.

With these and other disadvantages of the prior art in view, an object of the present invention is to provide a new and improved resonance synthesizer.

Another object of the present invention is to provide a new and improved resonance synthesizer having a switching means for minimization of inputs according to the type of sound.

Still another object of the present invention is to provide a new and improved resonance synthesizer capable of providing a mixed excitation necessary for certain sounds.

A still further object of the present invention is to provide a new and improved resonance synthesizer which is more versatile than those of the prior art.

Other objects and many of the intended advantages of this invention will be readily appreciated as the invention becomes better understood by reference to the following description when taken in conjunction with the following drawings wherein:

FIG. 1 is a block diagram of the preferred embodiment of the present invention.

FIG. 2 is a schematic diagram of the parameter switch shown in FIG. 1.

FIG. 3 is a schematic diagram of one of the four electronic switches of the parameter switch shown in FIG. 2.

FIG. 4 is a graphic illustration of various signals present in the excitation selector and mixer means shown in FIG. 1.

FIG. 5 is a block diagram of a resonance circuit shown in FIG. 1.

FIG. 6 is a block diagram of the amplitude control circuit of the resonance circuit shown in FIG. 5.

FIG. 7 is a schematic diagram of the conjugate pole resonance of the resonance circuit shown in FIG. 5.

THEORY

Referring now to FIG. 1, the resonance synthesizer of the present invention has two excitations circuits 10 and 11 and three spectrum shaping circuits 12, 13, and 14. The excitation circuits 10 and 11 consist of a random-noise generator 11 for turbulent excitation, and a pulse-generator 10, the frequency of which is variable logarithmically over the range 55 c.p.s.-330 c.p.s., for periodic excitation. For synthesis of women's and children's voices this range can be altered to 110 c.p.s.-660 c.p.s. by switching. The spectrum-shaping circuits 12, 13, and 14, consist of a vowel circuit 12, a nasal circuit 13 and a consonance circuit 14. The vowel circuit 12 is composed of four parallel formant resonances 17, 18, 19, and 20. The amplitudes (A_{17} , A_{18} , A_{19} , A_{20}) of these four resonances, and the frequencies of the lowest three (F_{17} , F_{18} , F_{19}) are dynamically variable; the frequency of the fourth, F_{20} , is manually variable, the manual adjustment being made by a screw adjustment on the synthesizer 22. A nasal circuit 23 is a single resonance of dynamically variable frequency F_N and amplitude A_N . The consonant circuit 14 consists of two parallel resonances 24 and 25 of dynamically variable frequency F_{K24} and F_{K25} , and amplitude A_{K24} and A_{K25} . The bandwidths of all resonances are manually variable. The amplitudes are variable over a 50 db range. The ranges over which resonance frequencies and bandwidths are variable are:

Resonance	Frequency, c.p.s.	Bandwidth c.p.s.
First vowel resonance 17	200-1,100	70-330
Second vowel resonance 18	700-3,200	70-330
Third vowel resonance 19	1,500-3,800	70-330
Fourth vowel resonance 20	2,500-4,500	70-330
Nasal resonance 23	100-400	70-330
First consonant resonance 24	1,000-6,600	200-500
Second consonant resonance 25	2,500-10,000	200-500

The synthesizer 22 has four states, selected by a two-bit switch function, S_{xx} , shown illustratively in FIG. 4, generated from an analogue input device 28. Each bit has two states, either 0 or 1. The first bit selects the spectrum-shaping circuits; and assigns the control functions to the appropriate parameters; the second bit determines the form of the excitation. Each state is appropriate for particular types of speech sound.

When the first bit state is 0, the vowel resonances 17, 18, 19, and 20, and the nasal resonance 23, operate in parallel and the consonant resonances 24 and 25 outputs are switched out. The dynamic parameters are F_0 , F_{17} , F_{18} , F_{19} , F_N , A_{17} , A_{18} , A_{19} , A_{20} , and A_N . When the first bit state equals 1, the nasal resonance 23 and the fourth vowel resonance 20 are replaced by the two consonant resonances 24 and 25, F_{17} assumes a manually preset value, and the dynamic parameters are: F_0 , F_{18} , F_{19} , F_{K24} , F_{K25} , A_{17} , A_{18} , A_{19} , A_{K24} and A_{K25} . Thus, even though the synthesizer 22 has a total of 14 dynamic parameters in addition to the two-bit state function, S_{xx} , only 10 control functions (parameters) are needed at any one time. F_N , F_{17} , A_N , A_{20} alternate with F_{K24} , F_{K25} , A_{K24} , and

A_{K25} , respectively, under control of the first bit of the state function.

When the second bit of the state function equals 0, the excitation is random noise. F_0 is, of course, superfluous. When the second bit of the state function equals 1 and the first bit of the state function equals 0, the excitation is periodic; when a second bit of the state function equals 1 and the first bit of the state function also equals 1, the excitation is mixed: noisy and periodic in varying proportions for the three vowel resonances 17, 18, and 19, and the consonant resonances 24 and 25. The mixture for each resonance is provided by means of the excitation selector and mixer network 29.

The state wherein the first bit of the state function is equal to 0 and the second bit of the state function is also equal to 0, is appropriate for *h*-like sounds, vowel onsets after voiceless consonants and whispered vowels. The state wherein the first bit equals 0 and the second bit equals 1 is appropriate for semi-vowels, vowels, nasals, nasalized vowels, liquids, and the closure periods of voice stops. The state wherein the first bit equals 1 and the second bit equals 0 is appropriate for voiceless fricatives, affricates and stop bursts. The state wherein the first bit equals 1 and the second bit also equals 1 is appropriate for voiced fricatives, and affricates and noisy liquids and semi-vowels.

Since the switching function is rather complex, overall performance depends to a large extent on the quality of the switching circuits 30, shown in detail in FIGS. 2 and 3. Bilateral transistors 33, 34, and 35, are used so as to minimize distortion and reduce the complexity of the circuits.

The conjugate pole pair resonances 36, shown in FIG. 5, and in more detail in FIG. 7, will be simulated by second-order operational amplifier loops, such as shown in FIG. 7. Since recent performance improvements and price reductions have made them very attractive, operational amplifiers will be used to a great extent throughout the synthesizer 22. Their use makes the output of the synthesizer 22 readily predictable from its input, simplifies calibration procedures, facilitates modifications and assists in maintenance.

The conversion of the synthesizer 22 control functions will be implemented by using anti-logarithmic modulators 37 for the fundamental frequency and the amplitudes of the resonance inputs, as shown in FIG. 6, and pulse-width modulators 38 for the resonance frequencies, as shown in FIGS. 1 and 5. A stable internal clock 39 is included to provide a quality time-base for the pulse-width modulators 38.

There are a number of methods by which the synthesizer 22 of the present invention may be driven. For example, it may be driven by a mechanical function generator which converts hand-painted parameter functions to control voltages; by a punched tape to be mounted on a motor-driven set of pulleys, with suitable decoding circuitry; by a digital magnetic tape; by a laboratory computer with a digital-to-analog converter; or by a large central computer with a time-sharing system, operating in conjunction with a laboratory digital-to-analog converter. The choice would depend upon the needs and resources of the particular users. All methods except the first require a computer. In the second and third methods the computer operates off-line to generate a control tape; in the fourth and fifth methods the computer operates on-line. For the first method, modification of the synthesizer to operate the switching function, S_{xx} , by an analog control function is required; otherwise, the two bits of the state function are transmitted to the synthesizer digitally. In the case of the fifth method, it would be desirable to set the synthesizer clock by means of a digital duration signal from the computer. The synthesizer would then request new control values only when the values actually changed, rather than at fixed intervals, and so free the computer for other work.

5 OPERATION

The synthesizer 22 of the present invention uses an analog input device 28 as a parameter generation means for driving the synthesizer 22. Eleven channels of the analog input device 28 are utilized. One channel provides the switch function S_{xx} . One channel provides the pitch frequency, F_0 , which controls the rate of pulse excitation. Five channels provide the input parameters A_{17} , A_{18} , F_{18} , A_{19} , and F_{19} . The remaining four channels provide an input to the parameter switch 42 which will yield eight other speech signal control parameters F_{17} , A_{K24} , A_{20} , F_{K24} , F_N , A_{K25} , A_N , and F_{K25} . The remaining speech parameter F_{20} is accomplished by means of a screw adjustment 43 on the synthesizer 22.

The input parameters A_{17} , A_{18} , F_{18} , A_{19} , and F_{19} , are fed into a parameter filter 44 before passing on to the synthesizer 22 and the respective resonance circuits 45. This parameter filter 44 filters out transients from the parameter control signals, due to the parameter generation. The five parameters A_{17} , A_{18} , F_{18} , A_{19} , and F_{19} , which are passed directly to the synthesizer 22 after passing through the parameter filter 44 are the input parameters which have been determined to be the necessary speech ingredients for most speech sounds.

PARAMETER SWITCH

The parameter switch 42, shown in FIG. 2, which yields the parameters F_{17} , A_{K24} , A_{20} , F_{K24} , F_N , A_{K25} , A_N , and F_{K25} from the four-channel input from the analog input device 28, selects those parameters which are necessary for either the nasal sounds or the fricatives. The amplitude (A) parameters, taken both directly from the analog input device 28 and the parameter switch 42, are amplitude control functions; the frequency (F) parameters are center frequency control functions. Referring now to FIGS. 1, 2, and 3, the parameter switch 42 consists of four electronic switches 30 connected in parallel across two input leads, 50 and 51, both carrying the switch function S_{xx} , each switch 30 having a parameter output pair, 47, 48, and an external input device 49.

Referring specifically now to FIG. 3 which shows a detailed schematic diagram of one of the four electronic switches 30 of the parameter switch 42, the external input device 49 may be utilized to provide any external voltage source capable of supplying some non-zero input to the electronic switch 30. If desired, the external input 49 may be set to "0." The electronic switch 30 consists of three transistors 33, 34, and 35; and three operational amplifiers 53, 54, and 55, with associated circuitry. The switch function S_{xx} taken from the analog input device 28 determines the condition of the three transistors 33, 34, and 35. There are two leads 50 and 51 to the transistors of the electronic switch 30, each lead being connected to the channel containing the switch function S_{xx} . Both leads 50 and 51 contain the switch function, but may differ in voltage level. One of the two leads 51 goes to the transistor pair 33 and 35 which operate concurrently; the other lead 50 goes to the third transistor 34 which operates inversely to the operation of the transistor pair 33 and 35.

ELECTRONIC SWITCHES

The electronic switch 30 is a parallel switch wherein the switch is off when the respective transistor is on. The switch is a one-bit switch having two states. In the first state, when the transistor pair 33 and 35 are off, and the third transistor 34 is on, we have both the output of the first operational amplifier 53 through the third operational amplifier 55, and the output of the external input device 49 through the second operational amplifier 54. If it is desired to set the first output 47 to a given value, this can be accomplished by setting the value of the external input device 49, and both outputs 47 and 48 may then pass to the associated resonance circuits. If it is desired that the first output 47 be equal to "0," then the external input

6

device 49 may in reality be set to "0," or be replaced by grounding this connection. The value of this external input device 49 is the manually preset value discussed previously.

5 In the other state of the electronic switch 30, the transistor pair 33 and 35 is on, and the third transistor 34 is off. We then have the second output 48, that is the output through the third operational amplifier 55, equal to "0" due to the transistor 35 associated with this output 48 being effectively a ground, and the first output 47 being equal to the input parameter through the first operational amplifier 53 and on through the second operational amplifier 54; the external input 49 being grounded through its associated transistor 33, thereby having a zero output passing through 10 the first leg 47 to the resonance circuit associated with that leg. The selected parameter passes through the other output leg 48 to its associated resonance circuit. The output leg 47 passing the "0" to the associated resonance circuit effectively shuts this circuit off.

15 The parameters output of the parameter switch 42 can be broken down into two groups. These groups are known as phonemic groups; the first group being the nasal group comprising the parameters F_{17} , A_{20} , F_N , and A_N ; the second group being the fricative group comprising the 20 parameters A_{K24} , F_{K24} , A_{K25} , and F_{K25} . The nasal group is present when the first bit of the state function is equal to "0," and the fricative group is present when the first bit of the state function is equal to 1.

25 In addition to acting as a selection means for these two phonemic groups, the parameter switch 42 also acts as a filtering means to filter out transients, such as the "pops" and "clicks" due to switching, or the transients due to parameter generation. The transients are eliminated from the synthesizer 22 output by the action of the capacitors 35 57, 58, and 59 associated with the first 53, second 54, and third 55 operational amplifiers in the electronic switch 30, acting as filters for the generated parameters.

EXCITATION SELECTOR AND MIXER

A state function channel S_{xx} from the analogue input device 28, provides the input leads 50 and 51 to the parameter switch 42, which leads provide the parallel connection means for the electronic switches 30 which make up the parameters switch 42, also it is connected directly 45 to the synthesizer 22 though a second switching means 62. The second switching means 62 is composed of a mechanical switch 63 and a Boolean "AND" function circuit 64. The switch 62 together with the pulse source 10 and the noise source 11 provide the inputs for the excitation 50 selector and mixer 29.

The pulse source 10 may be of the conventional type, not shown, consisting of a function generator, a voltage controlled oscillator, and a standard pulse generator, wherein the F_0 pitch frequency parameter is converted to 55 an approximate exponential function in a standard two-break-point diode function generator, which drives the linear voltage controlled oscillator; the output of the voltage controlled oscillator triggering the pulse generator so as to yield an output pulse excitation whose width is constant and whose frequency is an exponential function of the F_0 parameter input.

The noise source 11 may also be conventional wherein 60 a noise diode, the output of which is amplified by 60 db, low-pass filtered and then amplified again by 20 db, so as to yield a noise power which is approximately constant over the frequency range of 100 to 8000 c.p.s., is used to provide the noise excitation.

The second switching means 62 provides the synthesizer 70 22 with the mixed excitation capability mentioned previously. The pulse 10 and noise 11 excitations may be mixed to obtain a multiplicative output in the state when the first bit of the state function is equal to 1 and the second bit of the state function is also equal to 1. This multiplicative output will only occur in this state.

Referring now to FIG. 4 which is a graphic illustration of various signals present in the input to the excitation selector and mixer 29, S_{xx} represents the state function input to the second switching means 62, P_0 represents the pulse excitation 10 input to the Boolean "AND" function circuit 64, and to the excitation selector and mixer 29; $S_{11}(P_0)$ represents the multiplicative output of the Boolean "AND" function circuit 64, this signal appearing only when both P_0 and S_{11} are present; N_0 represents the noise excitation 11 output; and $S_{11}(P_0)(N_0)$ represents the multiplicative output of the excitation switch 66 which is passed to the adder circuit 67 of the excitation selector and mixer 29.

The multiplicative output function of the Boolean "AND" function circuit 64, $S_{11}(P_0)$, is utilized in the excitation switch 66 to switch the noise excitation, N_0 , on through the excitation switch 66. The noise excitation N_0 only passes when both the multiplicative signal $S_{11}(P_0)$ and the noise excitation N_0 are present. In the S_{11} state, that is, when the first bit of the state function is 1 and the second bit of the state function is also 1, the excitation switch 66 does not allow the pulse excitation source 10 to pass by itself to the adder circuit 67. The adder circuit 67 of the excitation selector and mixer 29 is always present. In the S_{11} state the input to the adder is $S_{11}(P_0)(N_0)$ and the other input is equal to 0; the input to the excitation switch 66 being N_0 and $S_{11}(P_0)$. The signal P_0 is also passed to the excitation switch 66 but this switch 66 does not pass P_0 to the output and subsequently to the adder 67.

In the other three states in the four state function, when the first bit is equal to "0" and the second bit is equal to 1 (S_{01}), when the first bit is equal to 1 and the second bit is equal to "0" (S_{10}), and when the first bit is equal to "0" and the second bit is also equal to "0" (S_{00}), the second switching means 62 only passes the state function S_{xx} to the excitation switch 66. At these times P_0 and N_0 are also fed into the input of the excitation switch 66. In the S_{10} and S_{00} states, only N_0 is passed to the adder circuit 67, thereby yielding a continuous noise output. In the S_{01} state, only P_0 is passed to the adder circuit 67, yielding a continuous pulse output.

If an additive, $S_{11}(P_0)$ plus N_0 , instead of a multiplicative $S_{11}(P_0)(N_0)$ excitation in the S_{11} state is desired, this may be accomplished by merely allowing both P_0 and N_0 to pass at the same time through the excitation switch 66.

The excitation switch 66 may be a standard transistorized switch similar in nature to the parameter switch 42.

The output of the excitation switch 66 is fed to the adder 67 and then from the adder 67 to the pulse width modulator 38 to obtain a pulse width modulated waveform e_0 of the excitation input; the clock source 39 is used as a reference for the circuit, as is standard.

The clock source 39 provides the reference signal c in a conventional manner by utilizing the output of a stable crystal oscillator to generate a standard clock pulse and a stable triangular wave used in the pulse width modulators 38. The crystal oscillator may be a 100 k.c.p.s. oscillator for driving a two-stage counter in order to divide the frequency by a factor of four to yield a 25 k.c.p.s. signal. This signal then triggers a standard pulse generator whose pulses control the period of a ramp generating circuit, resetting the ramp each time a pulse occurs, yielding a clock source 39 output c which is a stable triangular wave, suitable for driving the pulse width modulator circuits 38.

RESONANCE CIRCUITS

The excitation selector and mixer output e_0 , and the output c of the clock source 39 are fed directly to the resonance circuits 45 shown in block form in FIGS. 5 and 6 and in detail in FIG. 7. There are seven resonance

circuits as was previously mentioned, four vowel circuits 17, 18, 19, and 20; one nasal circuit 23; and two consonant circuits 24 and 25. Each of these resonance circuits has an input consisting of the excitation selector and mixer output e_0 , clock source 39, an associated amplitude parameter A_x , and an associated frequency parameter F_x .

Referring now to FIG. 5, which is a block diagram of any of the resonance circuits of the present invention, each resonance circuit comprises a frequency position drive 38, which is in effect no more than a pulse width modulator, having an input of its associated frequency parameter and the clock source 39 signal c , and an output of the frequency control signal e_c ; an amplitude control anti-logarithmic circuit 37 having an input of the associated amplitude parameter A_x and the excitation selector and mixer output e_0 , and a multiplicative output of these two signals $(e_0)(A_x)$; and a conjugate pole pair resonance circuit 36 having an adjustable bandwidth, having an input of the frequency control signal e_c and the multiplicative amplitude control signal $(e_0)(A_x)$ and an output of the desired formant.

Referring now to FIG. 6, which is a block diagram of the amplitude control anti-logarithmic circuit 37 of the resonance circuit shown in FIG. 5, the amplitude control anti-logarithmic 37 circuit consists of an anti-logarithmic circuit 68, which yields a linear db output for a linear voltage input amplitude parameter; a balanced modulator 69 connected to this anti-logarithmic circuit 68, which removes the components of the multiplicative $(e_0)(A_x)$ signal in the band of interest that cannot be removed by the low-pass filter 70 which is connected to the balanced modulator 69 and from which the output of this amplitude-control anti-logarithmic circuit 37 is taken. The input to the balanced modulator 69, in addition to the linear output of the anti-logarithmic circuit 68, is the excitation selector and mixer output e_0 . Low-pass filter 70 gets rid of the unwanted components of the excitation selector and mixer output signal e_0 . Balanced modulator 69 gets rid of the unwanted components of the amplitude parameter signal A_x . Through the utilization of this amplitude control circuit 37 we can obtain an output signal which does not contain unwanted signals which appear throughout the multiplicative output signal $e_0(A_x)$.

Referring now to FIG. 7 which is a schematic diagram of the conjugate pole pair resonance circuit 36 of the resonance circuits, the conjugate pole pair resonance circuit 36 is a modified second-order operational amplifier loop, having two inputs 71 and 72, as can be seen from examining FIG. 7. The first input 71 is to the transistor pair 73 and 74 and the second input 72, which is the output of the amplitude-control circuit 37, is to the circuit 36 across a variable resistance 75. The two transistors 73 and 74 shown in FIG. 7 change the mode of the loop from an operate to a hold condition at a rate which is at least twice as high as the highest frequency of interest. The circuit output in the operate condition is that of a conjugate pole pair network, such as a common R-L-C network. By controlling the amount of time the circuit is in the operate mode, the frequency location of the poles may be varied, so that the output impulse response in time will be of the form:

$$h(t) = e^{-at} \sin M\omega_R t, \quad 0 \leq M \leq 1$$

where M is the fraction of time the circuit is in the operate mode and ω_R is the natural frequency of the circuit.

The switching function performed by the two transistors 73 and 74 is accomplished by using the low collector to emitter resistance of the junction transistors operated in the inverted configuration shown in FIG. 7. The frequency control signal e_c , which is fed to the input 71 to the transistor pair 73 and 74, and which controls the state of the transistors 73 and 74, is, as was previously mentioned, generated by a pulse-width modulator 38 known as the frequency position drive source 38, the input of which is

the frequency control parameter F_x , which determines the pulse width.

The conjugate pole resonance circuit 36 has a manually adjustable bandwidth, being adjustable by means of the variable resistance 75. The frequency control signal e_c controls the transistor switches 73 and 74 to switch the circuit from the hold (off) to the operate (on) mode. The frequency control signal e_c is either positive or negative; when it is positive the circuit is on, and when it is negative the circuit is off.

When the frequency parameter F_x is 0, we are operating in the lowest frequency in our desired range. This is due to an in-circuit adjustment of the frequency position drive source 38, which is standard in this type of circuitry.

The output of the resonance circuit is taken from the conjugate pole resonance circuit 36. We have a choice of three outputs 76, 77, and 78 which may be selected by means of a switch 80. The outputs 76, 77, 78 are dependent upon which point in the conjugate pole resonance circuit 36 the output is taken. The first output 76, which is the normal output is taken at the output of the second operational amplifier 81; a second output 77 may be taken at the output of the third operational amplifier 82, said output being the negative from a normal output; and a third output 78 may be taken as the output of the first operational amplifier 83, said output being a negative of the normal output with a spectral zero-at-zero frequency. The normal output of the resonance circuit is the convolution of the multiplicative signal $e_0(A_x)$ and the impulse response of the conjugate pole resonance circuit 36; such output being a formant.

The fourth vowel resonance circuit 20 operates in the same manner as the other resonance circuits, except that the input frequency parameter F_{20} is a manually variable frequency arrived at by an internal potentiometer adjustment, F_{20} being internal to the synthesizer means 22.

During the operation of the resonance circuits, input parameters A_{17} , A_{18} , and A_{19} are always present in the synthesizer 22 and therefore in the associated resonance circuits. If desired, these parameters could be set to 0. Input parameters A_{K24} , A_{20} , A_{K25} and A_N are switched by the state function S_{xx} in the parameter switch 42 so as to select the desired parameters to be passed to the associated amplitude control circuit 37. The amplitude of the resonance circuit 45 input is controlled by an anti-logarithmic circuit 68, as explained previously. The converted amplitude control parameter is multiplied by a pulse-width modulated form of the selected excitation in a balanced modulator 69, and the resultant product is low-pass filtered through a low-pass filter 70 to remove unwanted extraneous components in the modulation product. The output is then the selected excitation at an amplitude which is proportional to the anti-logarithm of the input amplitude parameter. The amplitude parameters are critical factors which determine whether or not the resonance circuits are on; the amplitude parameters not being passed to the resonance circuits being equivalent to "0." The frequency parameter inputs to the resonance circuits are important in that they control the resonant frequency of the associated resonance circuits.

OUTER MIXER

The selected outputs of these resonance circuits 45, which are speech formants, are then passed into an output mixer 84. The output mixer 84 accomplishes summation of these speech formants and final low-pass filtering to produce connected speech sounds from these formants so as to form words by combining the formants to form phonemes, and phonemes to form words. These words can be connected together in sentence form, and in ensuing paragraph form in any desired speech arrangement.

The resonance synthesizer apparatus of the present invention thus makes use of the fact that only ten parameters (control functions) are necessary for speech sounds

at any one time, thus allowing for more efficient and economical synthesis of speech.

It is to be understood that the above-described embodiment of the invention is merely illustrative of the principles thereof and that numerous modifications and embodiments of the invention may be derived within the spirit and scope thereof; such as, utilizing individual excitation selector and mixer circuits for each of the resonance circuits so as to provide each with a separate and distinct mixed excitation output.

What is claimed is:

1. A resonance synthesizer comprising:
  - a parameter generating means for generating dynamically variable speech signal parameters and at least one state function;
  - a parameter switching means for selecting a desired phonemic group from said speech signal parameters;
  - a speech synthesizer means, having at least one state, for synthesizing the speech signal parameters to form connected speech sounds wherein less than all the generated speech signal parameters and at least one state function are utilized to control the speech output of the synthesizer;
  - a first plurality of connecting means, for connecting the parameter generating means to the speech synthesizer means and to the parameter switching means, the parameter switching means being connected to the parameter generating means by less than the total number of first connecting means; said state function being passed to the parameter switching means and to the synthesizer means by at least one of the first plurality of connecting means; and
  - a second plurality of connecting means, for connecting the parameter switching means to the synthesizer means wherein less than all the speech signal parameters passed to the parameter switching means by less than the total number of first connecting means are passed to the synthesizer means by less than the total number of second connecting means so that the desired phonemic group is passed to the synthesizer means.
2. A resonance synthesizer in accordance with claim 1 wherein said first plurality of connecting means includes a parameter filtering means for filtering at least one of the generated parameters of the total number of generated speech signal parameters, connected to the speech synthesizer means by the first plurality of connecting means so as to eliminate transients.
3. A resonance synthesizer in accordance with claim 2 wherein the parameter generating means is an analogue input device.
4. A resonance synthesizer in accordance with claim 3 wherein the analogue input device is a digital computer.
5. A resonance synthesizer in accordance with claim 3 wherein the parameter switching means is an electronic switching means comprising at least one electronic switch.
6. A resonance synthesizer in accordance with claim 5 wherein the electronic switch includes:
  - a transistor means;
  - an external input means for generating a desired external input speech signal parameter;
  - a first output comprising one of the generated speech signal parameters or the desired external input speech signal parameter; and
  - a second output comprising another generated speech signal parameter.
7. A resonance synthesizer in accordance with claim 6 wherein said state function passed to the parameter switching means controls the operation of the transistor means so as to select which output generated parameter to pass to the synthesizer means.
8. A resonance synthesizer in accordance with claim 4 wherein said electronic switch comprises:
  - a first input from the parameter generating means;
  - a first impedance connected to said first input;
  - a parallel second impedance;

a first operational amplifier connected in parallel with said second impedance;
a parallel third impedance;
a second operational amplifier connected in parallel with said third impedance;
a series fourth impedance connected between said first operational amplifier and said second operational amplifier;
a first transistor, having an emitter, base and collector, connected to the fourth impedance;
a fifth impedance connected to the base of the first transistor;
a first connecting means for connecting the fifth impedance and the number of connecting means of the first plurality of connecting means passing the state function to the parameter switching means and the synthesizer means;
an external input means for supplying desired external speech signal parameters;
a second input wherein said second input is the input from said external input means;
a sixth impedance connected between said second input and said second operational amplifier;
a second transistor, having an emitter base and a collector connected to the sixth impedance;
a seventh impedance connected to the base of the second transistor;
a second connecting means for connecting the base of the second transistor and the number of connecting means of the first plurality of connecting means passing the state function to the parameter switching means and the synthesizer means;
a series eighth impedance connected to the output of the first operational amplifier;
a parallel ninth impedance;
a third operational amplifier connected in parallel with said ninth impedance and in series with said eighth impedance;
a third transistor, having an emitter, base and collector, connected to the eighth impedance;
a tenth impedance connected between the base of said third transistor and the second connecting means;
a first and a second speech signal parameter output at the second and third operational amplifiers, respectively;
said second and third transistors operating together and inversely to the operation of the first transistor so as to pass only one of the two generated speech signal parameter outputs to the synthesizer means, said external input means passing the desired external speech signal parameter to the synthesizer means in addition to said passed one generated speech signal parameter when said second and third transistors do not operate and said first transistor does operate.

9. A resonance synthesizer in accordance with claim 8 wherein:

said parallel second, third and ninth impedances comprise a resistor and capacitor connected in parallel; said first, fourth, fifth, sixth, seventh, eighth, and tenth impedances comprise resistors; said first, second, and third transistors are connected to said fourth, sixth, and eighth impedances, respectively, by their respective bases; the respective emitters being grounded.

10. A resonance synthesizer in accordance with claim 9 wherein said second, third, and ninth impedance capacitors are filters for filtering the generated speech signal parameters so as to eliminate transients.

11. A resonance synthesizer in accordance with claim 10 wherein the electronic switching means comprising at least one electronic switch comprises more than one electronic switch said electronic switches being connected in parallel across said first at second connecting means, each electronic switch having a separate input from the parameter generating means at the first input;

a separate desired input from the external input means

at the second input associated with one of the two generated speech signal parameters; and a separate output pair of two speech signal parameters to the synthesizer means, only one generated speech signal parameter of each output pair being passed to the synthesizer means, and the separate desired external input being passed to the synthesizer means when the generated speech signal parameter associated with the external input means is not passed to the synthesizer means.

12. A resonance synthesizer in accordance with claim 11 wherein said state function passed to the parameter switching means controls the operation of the transistors so as to select which output generated parameter to pass to the synthesizer means.

13. A resonance synthesizer in accordance with claim 7 wherein the speech synthesizer means comprise:

a first switching means having a first and a second input and an output, the first input being connected to the number of connecting means of the first plurality of connecting means passing the state function to the parameter switching means and the synthesizer means;

an excitation selector and mixer means having an input and an output, connected at the input to said first switching means at the output of the first switching means;

a pulse excitation source means, having an input and an output, the output being connected to the second input of said first switching means and to the input of said excitation selector and mixer means, and the input being connected to a parameter of the parameter generating means;

a noise excitation source means connected to the input of the excitation selector and mixer means;

a clock source means connected to said excitation selector and mixer means;

a plurality of resonance means connected to the excitation selector and mixer means, at least one of said plurality of resonance means being connected to the clock source means for producing speech formants;

a second switching means connected to the plurality of resonance means for selecting a desired output form of the formant; and

an output mixer means connected to the second switching means for yielding an output consisting of connected speech sounds.

14. A resonance synthesizer in accordance with claim 13 wherein the pulse excitation source input parameter is a pitch frequency parameter for controlling the rate of pulse excitation.

15. A resonance synthesizer in accordance with claim 14 wherein the first switching means includes a Boolean logic "AND" function circuit for combining the pulse excitation source output and the state function to obtain a first multiplicative output of the state function and pulse excitation source in at least one state of the state function.

16. A resonance synthesizer in accordance with claim 15 wherein the excitation selector and mixer means comprise:

an excitation switch said excitation switch being connected to the pulse excitation source means, the first switching means, and the noise excitation source means, for selecting the desired excitation combination;

an adder circuit connected to the excitation switch for adding the desired excitation combination; and

a pulse-width modulator means connected to the adder circuit and to the clock source means for obtaining a desired excitation output to pass to the plurality of resonance means.

17. A resonance synthesizer in accordance with claim 16 wherein said excitation switch is an electronic switch.

18. A resonance synthesizer in accordance with claim 17 wherein said state function passed to the first switch-

ing means, and by said first switching means to said excitation switch, controls the operation of the electronic excitation switch so as to control the mixing of the pulse and noise excitation source means.

19. A resonance synthesizer in accordance with claim 18 wherein in the state of said state function, when the pulse excitation source is multiplicative with the state function the noise excitation source is fed into the excitation switch means by the first switch means to obtain a second multiplicative output of the state function, pulse excitation source and noise excitation source.

20. A resonance synthesizer in accordance with claim 19 wherein said plurality of resonance means comprises vowel resonance means, nasal resonance means, and consonant resonance means.

21. A resonance synthesizer means in accordance with claim 20 wherein said vowel resonance means comprise first, second, third and fourth vowel resonance circuits, said nasal resonance means comprise a nasal resonance circuit, and said consonant resonance means comprise a first and second consonant circuit.

22. A resonance synthesizer means in accordance with claim 21 wherein all resonance circuit means have associated manually variable bandwidths.

23. A resonance synthesizer in accordance with claim 22 wherein said dynamically variable speed signal parameters comprise a first type and a second type.

24. A resonance synthesizer in accordance with claim 23 wherein said first type is amplitude and said second type is frequency, each parameter being associated with a selected resonance circuit.

25. A resonance synthesizer in accordance with claim 24 wherein the amplitude parameters control the output of the resonance means so as to pass the desired speech formants to the output mixer means through the second switching means, for obtaining the desired connected speech sound output of the synthesizer means.

26. A resonance synthesizer in accordance with claim 25 wherein the resonance circuits each have an associated frequency parameter input, a dynamically variable amplitude parameter input, a clock source input, and an input of the excitation output, and an output of the desired speech formant.

27. A resonance synthesizer means in accordance with claim 26 wherein the resonance circuits each comprise:

- a frequency position drive source having an input of the clock source and of the associated frequency parameter and an output of a frequency control signal;
- an amplitude control circuit having an input of the associated dynamically variable amplitude parameter and of the excitation output, and an output of an amplitude control signal; and
- a first conjugate pole resonance circuit having the associated manually variable bandwidth and having an input of the frequency control signal output and of the amplitude control signal output, and an output

of the desired speech formant to the output mixer means.

28. A resonance synthesizer in accordance with claim 27 wherein the amplitude control circuit is anti-logarithmic and comprises:

5 an anti-logarithmic circuit having an input of the associated dynamically variable amplitude parameter in the form of a linear voltage input, and an output in the form of a linear decibel output of the linear voltage input;

10 a low-pass filter; and

a balanced modulator circuit, connected between the anti-logarithmic circuit and the low-pass filter and having an input of the anti-logarithmic output and of the excitation output for forming a third multiplicative amplitude control signal output and for removing the unwanted components of the third multiplicative output not removed by the low-pass filter.

29. A resonance synthesizer means in accordance with claim 28 wherein the associated frequency parameter inputs of the first, second, and third vowel resonance circuits, the nasal resonance circuit, and the first and second consonant resonance circuits are dynamically variable parameters obtained from the parameter generating means, and

25 the associated frequency parameter input of the fourth resonance circuit is a manually variable internal parameter.

30. A resonance synthesizer in accordance with claim 29 wherein the first and second conjugate pole resonance

35 circuits comprise a modified second-order operational amplifier loop having a first and second mode changing transistor connected to the circuit frequency control signal input and a first, second, and third operational amplifier having first, second, and third output connections, respectively, connected to the second switching means for obtaining the desired output form of the desired speech formant to be passed to the output mixer means.
